(57) **CLAIM**

The ornamental design for a rectifier for power supply, as shown and described.

DESCRIPTION

FIG. 1 is a front isometric view of a rectifier for power supply,

FIG. 2 is a front view thereof;

FIG. 3 is a rear view thereof;

FIG. 4 is a right side view thereof; and,

FIG. 5 is a left side view thereof.

1 Claim, 4 Drawing Sheets

FIG. 1

FIG. 2

FIG. 3

FIG. 4

FIG. 5
